UNITED STATES PATENT OFFICE.

CHARLES K. SMITH, OF FORT ATKINSON, IOWA.

PLASTIC-BLOCK-FORMING MACHINE.

Application filed October 20, 1925. Serial No. 63,652.

This invention relates to new and useful improvements in plastic block forming machines.

The primary object of the invention is to provide a machine especially adapted for forming from plastic material, such as cement or concrete, blocks suitable for use in erecting building walls, or the like.

A further object of the invention is to provide a novel form of core and core movement for the above referred to type of machine.

And a still further object of the invention is to provide a novel type of building block.

Other objects and advantages of the invention will be apparent during the course of the following description.

In the accompanying drawings forming a part of this specification and in which like numerals are employed to designate like parts throughout the same,

Figure 1 is a side elevational view of the block forming machine embodying this invention with the core arranged in its lowered position,

Figure 2 is an end elevational view of the structure shown in Fig. 1,

Figure 3 is a perspective view of the block forming machine with a pivotally mounted side wall of the molding box detached from its hinges and with the end walls swung into open position,

Figure 4 is a top plan view of the molding machine,

Figure 5 is a fragmentary vertical sectional view of the machine,

Figure 6 is a detail perspective view of the core shown in its lowered position,

Figure 7 is a top plan view of the novel form of building block produced by this machine,

Figure 8 is an end elevational view of the block, and

Figure 9 is a perspective view of the said block.

In the drawings, wherein for the purpose of illustration is shown a preferred embodiment of this invention, the numeral 5 designates in its entirety the stand portion 50 of the machine which is suitably reinforced by transverse end brace members 6 and has

mounted upon its upper end the bottom or base 7 of a mold box. The rear wall 8 of this mold box is rigidly connected to one longitudinal edge of the base 7 and has hinged-

ly connected thereto the end walls 9 which are provided with the vertically extending, parallel core guides 10, as best illustrated in Figs. 3 and 4. The front wall 11 of the mold box is formed with laterally and down-

wardly depending apertured ears 12 which are pivoted on the hinge pintle 13 fastened at its ends to the plates 14 carried by the upper portion of the base 5. This front wall 11 is roughened on its inner face 1 for forming a block with an ornamental outer face.

The inner faces of the remaining walls 8 and 9 are smooth. It is to be understood, however, that the inner face 15 of the front wall 11 may be smooth if desired and building blocks formed by the same will then have all of their faces of the smooth surface type. Figure 4 clearly shows the front wall 11 as having the edge flanges 16 against

which the free vertical edges of the end walls 9 bear for retaining the end walls against outward swinging movement on their hinges 17. Figs. 1, 2 and 4 clearly show the latch members 18 as being pivotally connected to the end edges of the rear wall 8 and as functioning to engage the pins 19 carried by the end edges of the hinged front wall 11 for locking this wall in its closed position.

Figs. 3 to 5 inclusive show the base 7 of the mold box as having a longitudinally extending slot 20 formed therein in vertical alignment with the grooves formed by the core guides 10 carried by the end walls 9. Depending from the base 7 and fastened to the ends of the stand 5 are metallic channel members 21 which act as guides for the opposite ends of the core 22 when the latter is arranged in its lowered position exteriorly of the mold box. This core 22 has its lower edge bolted to a rectangular frame 23 which has projections at its lower edge, designated by the reference characters 24, slidably arranged in the perpendicularly extending slots 25 formed in the channel members 21.

These ends 24 have laterally pivotally connected thereto the core actuating handles 26.

- These handles are employed for raising and lowering the core 22 in respect to the interior of the mold box. The various figures clearly illustrate the core 22 as being provided with transverse cuts 27 which extend from the top edge of the core 22 downwardly to points spaced inwardly from the bottom edge of the core.
- To prepare the machine for forming a block from plastic material, the end walls 9 are arranged in the position illustrated in Figs. 2 and 4. The front wall 11 is then moved into the position illustrated in Figs. 1, 4 and 5 with the free edges of the end walls 10 engaging the end flanges 16 of the front wall 11. The latch members 18 are then arranged to engage the laterally projecting pins 19 for locking the front wall 11 and end walls 9 in their closed positions.
- It is to be understood that the core 22 up until this time has been arranged in its lowered position, as clearly illustrated in Figs. 1, 2, 3, 4 and 6. The hand grips 26^a of the handles 26 are then grasped by the operator of the machine and the core 22 is elevated into the position illustrated in Fig. 5 with the top edge of the core aligned with the top edges of the various walls of the box. Figs. 2 and 6 clearly illustrate the operating handles 26 as having lateral notches 28 formed therein. After the core 22 has been moved into the mold box, the operating handles 26 are pivoted laterally on their pivot pins 29 for causing the notches 28 to engage the edges of the end boards 30, which are carried by the space 7. The engaging of these notches with the end boards 30 will hold the core 22 in its raised position.
- The plastic material employed for forming the type of blocks illustrated in Figs. 7 to 9 inclusive is then gradually placed in the assembled mold box and after enough of the material is arranged in the bottom of the box and tamped to a level registering with the bottom ends 27^a of the cuts 27 in the core 22, the lower tie rods 31 are placed in the box and upon the lower ends 27^a of the said cuts 27. Additional plastic material is then placed in the mold box and tamped down until the material reaches a suitable depth for positioning the upper tie rods 31 thereupon. These upper tie rods are then arranged in the cuts 27 and the remainder of the material is placed in the box and tamped down. To remove the molded blocks from the forming machine, the core operating handles 26 are pivoted to disengage their latch notches 28 from the boards 30 and then the core 22 is lowered into the channel members 21. This lowering or downward movement of the core 22 is considered as constituting a material improvement in the art as any pull upon the material produced by the movement of the core away from the same

will be prevented from tearing the material due to the fact that the latter is supported by the base 7 of the mold box against the pulling force of the core 22.

After the core has been lowered to its inoperative position, the latch members 18 may be disconnected from the pins 19 and the front wall 11 will then be free to be swung, as illustrated in dotted lines in Fig. 5, into a position away from the front face 75 of the building block. The end walls 9 may then be pivoted on their hinges 17 and the block removed.

Figures 7 to 9 inclusive clearly illustrate the novel form of building block produced by this machine. This block includes the sections 32 which are of substantially equal size and are retained in spaced parallelism by the tie rods 31 which are embedded at their ends in the material forming the parts 85 32. As has been previously described, the front face 33 of the block may be formed with an ornamental surface or with a plain surface.

It is to be understood that the form of this invention herewith shown and described is to be taken as a preferred example of the same, and that various changes in the shape, size, and arrangement of parts may be resorted to without departing from the spirit 95 of the invention or the scope of the subjoined claims.

Having thus described the invention, I claim:

1. A machine of the class described comprising a stand, a mold box mounted thereon, a core vertically movable through the bottom of said box adapted when raised therein to divide said box into two independent compartments and provided with a plurality of transverse slots for receiving tie rods, lifting handles connected to the ends of the core and arranged outwardly of the ends of the mold box, means to releasably retain the core in raised position, and a carrier upon which the core is mounted having end extensions to which said handles are pivoted at their lower ends for lateral swinging movement, said core retaining means embodying members fixed to the ends of the stand and engageable by the handles when swung laterally after the core is raised.

2. A machine of the class described comprising a stand, a mold box mounted thereon, a core vertically movable through the bottom of said box adapted when raised therein to divide said box into two independent compartments and provided with a plurality of transverse slots for receiving tie rods, lifting handles connected to the ends of the core and arranged outwardly of the ends of the mold box, means to releasably retain the core in raised position, a carrier upon which the core is mounted having end extensions to which said handles are pivoted at their 130

lower ends for lateral swinging movement, said core retaining means embodying members fixed to the ends of the stand and engageable by the handles when swung laterally after the core is raised, and channel guides for the ends of the core fixed to the ends of the stand beneath the mold box to

guide the core when lowered, said guides having longitudinal elongated slots outwardly through which the end carrier extensions project and are vertically movable. ¹⁰

In testimony whereof I affix my signature.

CHARLES K. SMITH.
